UNITED STATES PATENT OFFICE.

HAROLD P. BROWN, OF NEW YORK, N. Y.

HOLLOW CONCRETE WALL.

1,329,699.

Specification of Letters Patent.

Patented Feb. 3, 1920.

Application filed March 3, 1917. Serial No. 152,373.

To all whom it may concern:

Be it known that I, HAROLD P. BROWN, a citizen of the United States, and resident of the borough of Manhattan, in the city 5 and State of New York, have invented a new and useful Hollow Concrete Wall, of which the following is a specification.

My invention relates to a hollow wall and the method of constructing it, with the object in view of providing in an expeditious 10 manner, a strong and durable wall free from joints, air and water tight, and a good heat insulator.

My invention lends itself readily to the 15 construction of a monolithic wall, curved, straight, or any other desired form.

In the accompanying drawings,

Figure 1 represents in elevation, a portion 20 of a cylindrical wall, partly broken away to disclose the metallic reinforcing structure and the removable interior forms.

Fig. 2 is a horizontal section taken in the plane of the line II—II of Fig. 1, and

Fig. 3 is a horizontal section of a straight 25 wall.

In constructing the wall, either curved, straight, or other desired form, the reinforcing structure is first set up. This reinforcing structure consists of uprights 1 set 30 up at intervals against or in proximity to a removable exterior plate or back 2, which is oiled to prevent the adhesion of concrete. The uprights 1 are conveniently channel iron or rods.

Horizontal rods 3 are secured in any well 35 known or approved manner to the uprights 1 and are located at suitable intervals apart. From the uprights 1, in the structure shown in Figs. 1 and 2, from each alternate upright, and in the structure shown in Fig. 3, from every fourth upright, V-shaped brackets 4, conveniently formed by bending a rod 40 into V-shape, extend horizontally inward. The brackets 4 have their apices secured to the uprights 1 and are located at suitable 45 intervals, in the present instance at intervals one-half those between the horizontal rods 3, and so arranged on an upright that there will be a bracket in the plane of each 50 horizontal rod and one-half way between two consecutive horizontal rods.

An inner series of uprights 5, one at the 55 end of each arm of the bracket 4, and one or more intermediate of two horizontally successive brackets, have the arms of the brackets secured thereto and also have se-

cured thereto an inner series of horizontal rods 6 corresponding to the rods 3. A rigid self-supporting reinforcing structure is thus formed consisting of inner and outer skeleton parts connected by the V-shaped brackets. Diagonal rods 3*, one of which is shown in dotted lines in Fig. 1, are secured to the uprights at or near the upper opposite corners of an opening 13 in the wall and extend downwardly and are fastened to the adjacent upright or series of uprights having the brackets 4 thereon. The opening 13 may be used as a door or window for the structure.

The reinforcing structure as above described having been set up in front of or against the exterior oiled plate or back 2, the primary wall section 7 is formed by jetting concrete or other plastic material against 70 the plate or back 2, embedding the uprights 1 and horizontal reinforcing rods 3. The hinged forms 8 are then set in position between consecutive vertical series of brackets 4, the edges of the flaring sides of the forms 80 8 closely engaging the face of the primary wall 7 and the inner faces of the forms occupying positions in proximity to the uprights 5, so that the said forms will be spaced from the rods 6 about the thickness 85 of the uprights 5.

The forms 8 having been placed in position and oiled to prevent adhesion of concrete, the secondary wall section 9 and webs 10 are constructed by jetting concrete or 90 other plastic material against the oiled surfaces of the forms 8, embedding the brackets 4 and the uprights 5 and rods 6 and adhering to the primary wall at the apices of the webs 10. The webs 10 having the V-shaped brackets embedded therein, thus 95 unite the primary and secondary wall sections as a single hollow wall.

The forms 8 are conveniently constructed in knock-down form, in the present instance 100 pins 11 being employed to temporarily lock the sides and front of the forms together, thus permitting the forms to be collapsed by withdrawing the pins, and removing the parts. The forms are made long enough to 105 reach from say the foundation wall to the level of ceiling of first floor. After the wall is poured to that height the forms are removed by taking out the pins from the top, collapsing the forms and taking them also 110 out from the top. The exterior plate or back 2 for the ceiling is then put into place

and held level by suitable removable supports. The proper reinforcement is then placed for the ceiling, the floor and the V-shaped reinforced floor beams joining them. 5 Concrete is then jetted downward to form the ceiling say $\frac{3}{4}$ in. to 1 in. thick. The forms 8 with their pins 11 in position are then slipped into place from outside and concrete is again jetted downward into the 10 V-shaped beams and over the reinforcement rods 5 and 9 of the floor. The jetted concrete sets up very quickly and the pins 11 of the forms can be removed from the side, the forms collapsed and removed also from the 15 side. The vertical reinforcement of the wall for the next story is then put in place and the process repeated for the next story, and so on to the roof.

The impact of the jetted concrete against 20 the surfaces of the plate 2 and the forms 8, gives it such density that it is waterproof and is far stronger than ordinary poured concrete. This permits the use of thin slabs for the primary and secondary strata and effects a large saving of material. The hollow construction makes the wall a good heat insulator. The same method of construction 25 can be used for floors and roofs of buildings. In this case the reinforcing rods 12, of said 30 floors or roofs shown in Fig. 3, may be turned downward at their outer ends into the concrete of the vertical walls, and especially into the concrete of the webs 10, which should, of course, be opposite each other. 35 The same construction can be used for the hulls and decks and bulkheads of barges and ships. To secure greater safety, strength and lightness in marine construction, a third or even a fourth inner wall stratum 40 can be formed in the same manner as the secondary stratum. The exterior plate 2 can be shaped to produce the curving contour of the sides of the ships and the concrete jetted from within. In this case, the forms 8 can 45 be used without oil and left in place.

What I claim is:

1. The method of constructing a reinforced concrete wall, consisting of first setting up two parallel self-supporting layers 50 of reinforcement joined at suitable intervals by rigid brackets within which are placed the necessary reinforcing rods for the studding; second, of jetting concrete for the first layer of the wall; 3d, of placing in position 55 against the layer already completed, forms to shape the sides of the studding and the inner surface of the second layer of the wall; 4th, of jetting concrete to complete the

studding and construct the outer layer of wall.

2. The method of constructing a reinforced plastic wall, consisting in first setting up the reinforcing elements, secondly, forming a section of the wall, then placing hinged forms in position against the wall section 65 already formed, thirdly, applying plastic material over and between said forms to form a second wall section with webs connecting with the wall section first formed and finally removing said forms.

3. The method of constructing a reinforced concrete wall consisting of first setting up two parallel, self-supporting reinforcing layers joined at suitable intervals by rigid brackets; 2nd, of jetting concrete for the 75 first layer of the wall, 3d, of placing in position against said first layer collapsible forms to shape the sides of the studding and the inner surface of the second layer of the wall; 4th, of jetting concrete for the studding and second layer of the wall; 5th, of collapsing and removing said forms.

4. The method of jetting upon one side of a self-supporting frame of reinforcement, two successive layers of concrete to form 85 parallel wall sections united at suitable intervals by reinforced concrete webs.

5. The method of constructing a reinforced monolithic concrete wall consisting in first setting self-supporting reinforcement; 90 2nd, of jetting plastic concrete to form a wall section partially embedding the reinforcements; 3d, of placing forms at intervals against the wall section first made, and finally applying plastic concrete over and 95 between the forms, embedding the reinforcement and connecting with the wall section first formed.

6. The method of constructing a reinforced concrete wall consisting in first setting up a self-supporting reinforcement of two parallel elements united by occasional webs and backed by a removable plate; 2nd, in jetting plastic concrete against the plate to make a wall section, embedding a part of 100 the reinforcement; 3d, in setting up forms at intervals within the reinforcement and against the wall section already made; 4th, in jetting plastic concrete on to the forms, thereby building up a second wall connected 105 with the first section and having embedded therein the reinforcement.

In testimony, that I claim the foregoing as my invention, I have signed my name this 26th day of February, 1917.

HAROLD P. BROWN.
